LOCOMOTIVE FEED WATER SYSTEM

Joel S. Coffin, Jr., Englewood, N. J., assignor to
C-S Engineering Company, Englewood, N. J., a
Corporation of Delaware

Application January 28, 1929. Serial No. 335,404

12 Claims. (Cl. 122—441)

This invention relates to locomotive feed water heater systems, and especially to the feed water heater itself and the distribution of steam thereto and therethrough.

5 One of the primary objects of the invention is the simplification of the installation of feed water heaters on locomotives, as well as of the steam distribution thereto.

Another object of the invention is the reduction of the number, size and cost of the parts required in such an installation, with a co-incident improvement in general appearance of the heater-equipped locomotive, saving of valuable space, and increase in accessibility of the heater and 10 connections.

Other objects of the invention include the provision of a heater construction applicable to the front-end or smoke-box of a locomotive, either externally or in a recess therein, with a reduction 15 in overall length of the heater forward of the smoke-box (or of the smoke-box itself, in internal installations); the maintenance of the requisite pipe connections below the centre line of the smoke-box; the reduction of piping lengths 20 and simplification of joints; the obviation of the practice of mounting piping and connections in the smoke-box itself, even where the heater is recessed therein; and the provision of convenient means for drainage or cleaning.

30 How these objects and advantages, together with such others as are incident to the invention or will occur to those skilled in the art, are attained, will be clear from the following description, taken together with the accompanying drawings; in which drawings:

Figure 1 is a front elevation of the present heater and associated structure, in the position in which it is applicable to the front-end of a locomotive, certain parts being in section, and others broken away to show the structure behind them;

40 Figure 2 is a view taken from the right of Figure 1, but with different parts broken away or in section, this view corresponding to a view from the left-hand side of a locomotive to which the heater would be applied;

45 Figure 2a is a side view of the forward portion of a locomotive, with the heater of the present invention applied thereto and with the various connections clearly illustrated as being extended to the lower ends of the heater in the manner referred to above;

50 Figure 3 is a section taken on the line 3—3 of Figure 1; and

Figure 4 is a section taken on the line 4—4 of Figure 1, but with the heater tubes omitted.

By reference to the drawings in general, it will be seen that I have illustrated a feed water heater construction having a casing formed of a front plate 2, a rear plate 3, upper and lower plates 4 and 5, and end or tube plates 6; the heater structure being semi-circular when viewed in front elevation (as in Figure 1), so as to be mounted at the front of a locomotive smoke-box for obtaining maximum practicable tube-length with minimum waste of space or encroachment on vision or clearance limitations. The water tubes 7, connected at their ends into the respective tube sheets, are of similar arcuate or semi-circular 60 form, and are preferably grouped into a plurality of passes, 7a, 7b, 7c, 7d and 7e (see Figs. 2 and 3), so that the water, fed into inlet 8 of inlet header 9, as by means of the supply pipe 8a (see Fig. 2a) passes first through the tubes of bank 7a 65 to the counterpart outlet header (not shown), then back through bank 7b to header chamber 10, from thence by way of bank 7c to a similar chamber of the opposite header, then through bank 7d, chamber 11 and bank 7e to the outlet 70 75 80 85 90 95 100 105 110

The two headers (only one of which is shown) are counterparts, relatively reversed in position, and are attached to the tube plates, for co-operation therewith, by bolts 12, 13. Drainage ports 14, 15, with plugs 16, are, respectively, provided for chambers 10 and 11, as well as washout plugs 17, one for each end of the tube-chamber itself.

The casing is preferably provided with tube positioning plates 18, hand-hole frames 19 adjacent thereto, and combined hand-hole covers and heater-lifting devices 20, the latter being firmly secured to the casing by studs 21 screwed into the frames 19. The casing at the back is provided with mounting pads 22 and studs 23 for attachment to the front of the smoke-box; while lagging plates 24, 25, 26, and retaining studs 27, may be provided for the front, the top, and the bottom of the heater, although it will be understood that the lagging, as well as the mounting studs 23, may be removed for recessed mounting of the heater in the smoke-box shell.

A vent 28 is shown at the top of the heater, and condensate outlet pipes 29 at the ends or legs thereof in the vicinity of the headers.

The heater, as best seen in Figure 4 is of elongated rectangular cross-section, with its narrow dimension radially of the heater as a whole, so as to provide ample clearance within its inner circumference for removal of locomotive parts

through the usual smoke-box door, as well as to keep its outer circumference within the outside circumferential surface of the smoke-box shell.

In its longer cross-sectional dimension (see

5 Fig. 4) the heater is divided, from front to back, into three chambers, 30, 31 and 32, by means of the partitions 33 and 34 which extend from end to end of the heater. Partition 33, preferably welded to casing plates 4 and 5, has one or more

10 steam apertures 35, there being three of them in this instance, one located at the centre of the heater and one at each side of the central one (two, only, being shown in Figure 1, because of the breaking away of a part of partition 33).

15 The other partition (34) is perforated with a multiplicity of holes 36, over substantially its entire area. This partition is preferably supported from the first by rivets and spacers, 37 and 38.

20 At the ends or legs of the heater I provide steam inlets 39, each welded at its upper end to a forward extension 6' of the tube sheet 6, and having at its lower end a downwardly and rearwardly directed flange 40, to which may be secured the flange 41 of a pipe 42 which extends diagonally downward for connection to the locomotive cylinder exhaust, as at 42a in Figure 2a. A ball ring 43 is preferably provided at the junction of conduits 39 and 42 to accommodate movements due to temperature changes. The connection from the heater to the boiler is clearly shown in Figure 2a at 8b.

From the description, hereinbefore, of the water tubes and headers, it will be evident that 35 the water, in its course through the heater, makes a plurality of passes from end to end of the heater, the first or coldest pass being the rear pass 7a (as seen in Fig. 3) and the last or hottest pass being the forward pass 7e. The 40 passes are, in other words, arranged serially from the rear to the front of the elongated chamber 32 (speaking with respect to the cross-sectional dimensions of the heater). Chambers 30 and 31, on the other hand, occupy relatively little space 45 in their corresponding dimension, since their cross-sectional area need be only sufficient to give clear passage to that quantity of steam which the heater itself is able to condense. Now it will be evident that the steam, in passing from the exhaust connections 42 into the receiving 50 connections or elbows 39, is directed from thence through passage or chamber 30, from each lowermost end thereof up to the centre or top of the heater. Here it passes through the apertures 35 of partition 33 into chamber 31 and flows downwardly in the two legs of this chamber. That is, the whole chamber 31 is filled with steam, and throughout the length of the chamber the steam 55 is directed in jets through the holes 36 into tube chamber 32, striking first the tubes of the last pass 7e, from end to end thereof, and in succession the other passes in like manner; the condensate collecting at the ends of the heater where it passes out through pipes 29.

60 The entire arrangement is such that, while the steam is uniformly distributed from end to end of the heater, (so that it may flow uniformly across the full length of the banks of tubes), yet the steam delivery pipes 42 may be connected at the two 65 ends of the heater at the very bottom, thus simplifying the connections, and eliminating cumbersome, expensive and unsightly piping arrangements above or in front of the heater or the smoke-box, as is clearly shown in Figure 2a. Furthermore, from Figure 2a it will be seen that all

connections are made outside the smoke-box, and all of them at the bottom of the heater, simplifying condensate drainage and steam delivery as well as the draining or cleaning out of header and heater chambers.

80 In installations where the heater is recessed into the smoke-box itself, the lower half of the smoke-box shell may be indented at the sides, immediately below the heater legs, so that all joints are compactly located just outside the shell.

85 The overall length of any installation of this heater, whether mounted in front of, or recessed in the front of, the smoke-box, is less than that of those heretofore used, by virtue of the elimination of considerable distributing piping, elbows and connections, while at the same time the steam distribution is improved and its path of travel shortened, and the general appearance of the locomotive enhanced.

90 In conclusion, especial attention is again called to Figure 2a which clearly illustrates the manner in which the various connections to the heater are extended to the lower ends thereof so as to provide for the reduction of piping lengths and simplification of joints; so as to obviate the practice of 100 mounting piping and connections in the smoke-box itself, it being noted with regard to this point that while the arrangement is shown in Figure 2a as being applied to the locomotive boiler externally thereof, even where the heater is recessed in the smoke-box, the connections, as hereinbefore brought out, may similarly be extended externally of the smoke-box; and so as to provide convenient and effective arrangements for taking care of drainage and cleaning.

105 What I claim is:—

110 1. In apparatus of the character described, an arcuate heater having a group of water tubes extending lengthwise therein, end enclosures for the heater with means for passing water through the tubes, a steam delivery chamber and a steam distributing chamber extending from end to end in the heater, jet openings spaced along a wall of the distributing chamber from end to end and directed transversely of the group of tubes, and a 115 steam port interconnecting the chambers adjacent the middle of the arc, together with means for feeding steam to the ends of the delivery chamber through said end closures.

120 2. An elongated semi-circular feed water heater having a casing with partitions dividing it into a plurality of curved chambers extending longitudinally thereof, water tubes in one chamber, a multiplicity of apertures in the partition adjacent thereto, a steam port in an adjacent partition, there being a chamber between said two partitions, and means for feeding steam into the end 125 of an adjacent chamber for delivery to said port.

130 3. An elongated feed water heater having a casing with partitions dividing it into a plurality of chambers extending longitudinally thereof, water tubes in one chamber, a multiplicity of apertures in the partition adjacent thereto, a steam port in an adjacent partition, there being a chamber between said two partitions, and means for feeding steam into the end 135 of an adjacent chamber for delivery to said port, together with a tube plate at an end of the casing having an aperture through which the steam is fed to said delivery chamber.

140 4. An elongated feed water heater having a casing with partitions dividing it into a plurality of chambers extending longitudinally thereof, water tubes in one chamber, a multiplicity of apertures in the partition adjacent thereto, a steam port 145

- in an adjacent partition, there being a chamber between said two partitions, and means for feeding steam into the end of an adjacent chamber for delivery to said port, together with a tube plate at an end of the casing serving as a closure for all the chambers and having a steam supply aperture opening into the delivery chamber. 80
5. In a locomotive feed water system, a substantially semi-circular inverted-U-shaped feed heater casing for co-operation with a smoke-box shell, water tubes extending lengthwise therein, water connection members adjacent the lower ends or legs of the casing delivering to and from said tubes, distribution means in the casing positioned to provide a chamber for steam distribution substantially uniformly endwise in the heater means for delivering steam from said chamber transversely across the tubes, and steam delivery means connected to the heater adjacent the said lower ends or legs thereof and delivering to said chamber. 85
- 10 6. In a locomotive feed water system, a substantially semi-circular inverted-U-shaped feed heater casing for co-operation with a smoke-box shell, water tubes extending lengthwise therein, water connection members adjacent the lower ends or legs of the casing delivering to and from said tubes, distribution means in the casing positioned to provide a chamber for steam distribution substantially uniformly endwise in the heater means for delivering steam from said chamber transversely across the tubes, and steam delivery means connected to the heater adjacent the said lower ends or legs thereof and delivering to said chamber, said delivery means and water connection members being substantially aligned fore-and-aft. 90
- 15 7. In a locomotive feed water system, a substantially semi-circular inverted-U-shaped feed heater casing for co-operation with a smoke-box shell, water tubes extending lengthwise therein, water connection members adjacent the lower ends or legs of the casing delivering to and from said tubes, distribution means in the casing positioned to provide a chamber for steam distribution substantially uniformly endwise in the heater, means for delivering steam from said chamber transversely across the tubes, steam delivery means connected to the heater adjacent the said lower ends or legs thereof and delivering to said chamber, and condensate drains for the casing positioned also adjacent the lower ends thereof. 95
- 20 8. In a locomotive feed water system, a substantially semi-circular inverted-U-shaped feed heater casing for co-operation with a smoke-box shell, water tubes extending lengthwise therein, water connection members adjacent the lower ends or legs of the casing delivering to and from said tubes, distribution means in the casing positioned to provide a chamber for steam distribution substantially uniformly endwise in the heater, means for delivering steam from said chamber transversely across the tubes, and steam delivery means connected to the heater adjacent the said lower ends or legs thereof and delivering to said chamber. 100
- 25 9. In a locomotive, an arcuate heater shaped to conform to the general shape of the locomotive at a point adjacent the front and top thereof and being mounted at such point, the heater having arcuate water tubes therein, having steam distribution means positioned to provide a chamber for steam distribution substantially uniformly endwise from the ends of the heater, having means for delivering steam from said chamber transversely across the tubes, and steam connections extending downwardly and rearwardly from the lower ends of the heater and connected with the locomotive exhaust steam. 105
- 30 10. In a locomotive, an arcuate heater shaped to conform to the general shape of the locomotive at a point adjacent the front and top thereof and being mounted at such point, the heater having arcuate water tubes therein, having steam distribution means positioned to provide a chamber for steam distribution substantially uniformly endwise from the ends of the heater, having means for delivering steam from said chamber transversely across the tubes, and steam inlet members secured to the lower ends of the heater, extending downwardly, and having conduit means attached thereto and connected with the locomotive exhaust steam. 110
- 35 11. In a locomotive, a substantially semi-circular inverted U feed water heater mounted adjacent the front end thereof, the heater having means for mounting it in the position aforesaid and having steam and water connection members at its lower ends, the steam connection members being connected with the locomotive exhaust steam and the water connection members being connected with the water supply pipe and the boiler, and an internal steam-conveying passage delivering adjacent the middle of the heater whereby external piping is minimized and is kept below the heater proper, while balanced steam distribution from the center to the ends of the legs of the heater is assured. 115
- 40 12. In a locomotive, a substantially semi-circular inverted U feed water heater mounted adjacent the front end thereof, the heater having means for mounting it in the position aforesaid and having steam and water connection members and drainage means all located adjacent to the ends of the legs of the arch, the steam connection members being connected with the locomotive exhaust steam, and the water connection members being connected with the water supply pipe and with the boiler, and an internal steam-conveying passage delivering adjacent the middle of the heater whereby external piping is minimized and is kept below the heater proper, while balanced steam distribution from the center to the ends of the legs of the heater is assured. 120
- 45 13. In a locomotive, a substantially semi-circular inverted U feed water heater mounted adjacent the front end thereof, the heater having means for mounting it in the position aforesaid and having steam and water connection members and drainage means all located adjacent to the ends of the legs of the arch, the steam connection members being connected with the locomotive exhaust steam, and the water connection members being connected with the water supply pipe and with the boiler, and an internal steam-conveying passage delivering adjacent the middle of the heater whereby external piping is minimized and is kept below the heater proper, while balanced steam distribution from the center to the ends of the legs of the heater is assured. 125
- 50 14. In a locomotive, a substantially semi-circular inverted U feed water heater mounted adjacent the front end thereof, the heater having means for mounting it in the position aforesaid and having steam and water connection members and drainage means all located adjacent to the ends of the legs of the arch, the steam connection members being connected with the locomotive exhaust steam, and the water connection members being connected with the water supply pipe and with the boiler, and an internal steam-conveying passage delivering adjacent the middle of the heater whereby external piping is minimized and is kept below the heater proper, while balanced steam distribution from the center to the ends of the legs of the heater is assured. 130
- 55 15. In a locomotive, a substantially semi-circular inverted U feed water heater mounted adjacent the front end thereof, the heater having means for mounting it in the position aforesaid and having steam and water connection members and drainage means all located adjacent to the ends of the legs of the arch, the steam connection members being connected with the locomotive exhaust steam, and the water connection members being connected with the water supply pipe and with the boiler, and an internal steam-conveying passage delivering adjacent the middle of the heater whereby external piping is minimized and is kept below the heater proper, while balanced steam distribution from the center to the ends of the legs of the heater is assured. 135
- 60 16. In a locomotive, a substantially semi-circular inverted U feed water heater mounted adjacent the front end thereof, the heater having means for mounting it in the position aforesaid and having steam and water connection members and drainage means all located adjacent to the ends of the legs of the arch, the steam connection members being connected with the locomotive exhaust steam, and the water connection members being connected with the water supply pipe and with the boiler, and an internal steam-conveying passage delivering adjacent the middle of the heater whereby external piping is minimized and is kept below the heater proper, while balanced steam distribution from the center to the ends of the legs of the heater is assured. 140
